UNITED STATES PATENT OFFICE.

JOHN H. MILLER, OF MACDUNN, WEST VIRGINIA.

DOOR.

Application filed September 18, 1922. Serial No. 588,950.

To all whom it may concern:

Be it known that I, JOHN H. MILLER, a citizen of the United States, residing at MacDunn, in the county of Fayette and 5 State of West Virginia, have invented new and useful Improvements in Doors, of which the following is a specification.

This invention relates to mine doors, and has for its chief characteristic, the provision 10 of means whereby the doors are automatically opened and closed by the car as it approaches the door entrance forming either side of the door.

More specifically stated, the invention 15 makes use of door sections mounted for sliding movement toward and away from each other, the doors being connected together by cables trained over suitable guide pulleys, and having associated therewith a weight 20 for returning the doors to closed positions, car actuated mechanism being arranged along the rails of the track at the opposite sides of the door opening, and operable as the cars approach the door opening to automatically move the doors to their opened 25 positions.

Another object of importance resides in the novel construction of each door, the latter being made up of a plurality of units 30 associated by double hinges to permit any one or more of said sections to be swung in either direction, so that the locomotive may pass through the door opening so that the doors become stuck, and also allows a person 35 or animal to pass through the door opening without actuating the door opening means above referred to.

The nature and advantages of the invention will be better understood when the following detailed description is read in connection with the accompanying drawings, the invention residing in the construction, combination, and arrangement of parts as 40 claimed.

45 In the drawings forming part of this application, like numerals of reference indicate similar parts in the several views, and wherein:—

Figure 1 is a view in elevation, showing 50 the doors in their normally closed positions.

Figure 2 is a top plan view.

Figure 3 is a longitudinal sectional view.

Figure 4 is a sectional view taken on line 4—4 of Figure 2.

55 Referring to the drawings in detail, A indicates a door frame of proper dimensions

for use in mines, the door opening being of a size to allow the passage therethrough of the mine cars. The track for these cars is obviously passed through the door opening 60 and indicated at 10. The door opening is normally closed by means of the sliding doors 12, the latter being movable along suitable tracks 13, and adapted to slide toward and away from each other as will be 65 readily apparent. The doors may be hung for this purpose in any suitable manner. These doors are connected by cables in a manner so that when one door is positively actuated by means to be hereinafter 70 described, movement is imparted to the other door, so that the door simultaneously opens and closes. As shown, one of these cables is indicated at 15, and has one end secured to one of the doors and its opposite end supporting a weight 16, which is elevated incident to the opening of the doors and utilized to automatically close the doors as the cars pass off the track. The cable 15 is trained over a guide pulley 17, which is mounted on 75 a suitable upright 18. The other of the cables for the purpose above mentioned is indicated at 19, and has its free end secured to the other of the doors, this cable being trained over a guide pulley 20 mounted on 80 a suitable bracket 21 to provide spaced runs. The other run of this cable is secured to the adjacent door, so that the doors are simultaneously actuated as above described.

The means for automatically opening the 90 doors as the cars approach the door opening is identical on both sides of the door opening, and which means includes a transverse shaft 22 journaled in suitable bearings 23 and provided at one end with an upwardly 95 extending lever 24. This lever is connected to one end of a cable 25 which is trained over a suitable pulley 26 supported by a post or upright 27, the cable passing from the pulley just mentioned onto a similar 100 pulley 28 mounted on the same upright, but arranged at a right angle to the pulley 26. The pulley 28 forms a part of a duplex pulley, inasmuch as it is associated with a larger pulley 29, and this pulley has secured thereto one end of a short cable 30 which is adapted to be wound about and unwound from said pulley to open and close the doors, this cable 30 being terminally connected to the adjacent door. Manifestly, when the shaft 22 is partially rotated in one direction, the lever 24 exerts a 105

pull upon the cable 25, which rotates the duplex pulley, causing the cable 30 to be wound about the pulley 29 and thus move the doors to opened positions. When the shaft is rotated in an opposite direction, the cable unwinds from the pulley 29 as the weight 16 gravitates to its lowered position. For the purpose of controlling the movements of the shaft 22, I employ a trip rail 32 which is pivoted at one end as at 33 on the adjacent rail of the track, and this rail is normally arranged at an inclination to the rail of the track, or in other words, slightly elevated therefrom to be depressed by the weight of the locomotive passing thereover. This tripping rail is equipped with a link 33, which in turn is connected with an arm 34 projecting from the shaft 22, the parts being arranged so that when the tripping rail is depressed, the shaft is partially rotated in the proper direction to move the doors to an open position in a manner above described. The lever 24 at the opposite sides of the door opening are connected by a cable 36 so that the levers are actuated simultaneously, irrespective of from which side of the door opening the cars approach said opening, and this cable 36 is trained over suitable guide pulleys 27 journaled in brackets 38.

It will be noted that each door is made up of a plurality of sections, the sections being connected together by double hinges 39 which permit these sections to be moved singly or in unison in either direction through the door opening, so that should the doors become stuck for any reason, the locomotive is allowed to pass through the door opening without injury to either the locomotive or the doors, and which construction also permits a person or an animal to pass through the door opening without opening the doors by means of the car actuated mechanism above described. The door sections are connected together by coiled springs or other resilient elements which pass through aligned openings in the door sections as shown.

While it is believed that from the foregoing description, the nature and advantages of the invention will be better understood, I desire to have it understood that I do not limit myself to what is herein shown and described, and that such changes may be resorted to when desired as fall within the scope of what is claimed.

What I claim is:

1. A mine door, comprising two door members mounted for sliding movement toward and away from each other, guide pulleys supported adjacent the door opening, cables trained over said pulleys, the adjacent ends of the cables being crossed and terminally secured to the door members, car actuated means operable to automatically

open the doors incident to the approach of the cars to the door opening, and means for automatically closing the doors incident to the release of said means.

2. A mine door composed of two door members mounted for sliding movement toward and away from each other, car actuated means operable to automatically open the doors, said means including a duplex pulley, the pulleys of which are of relatively different size, a cable connected to the latch of said pulleys and also to the adjacent door, a second cable connected to the latter mentioned door and trained over a pulley and having its terminal connected to the other door, a tripping rail adapted to be depressed by the weight of the cars, a connection between said rail and the duplex pulley for rotating the latter in a proper direction to open said doors, and means including a cable, and a weight suspended therefrom for automatically closing said doors as the cars pass off the rail.

3. A mine door, composed of two door members mounted for sliding movement toward and away from each other, a duplex pulley, the component parts of which are of relatively different size, a second pulley arranged at a right angle to the duplex pulley, a cable secured to one of the door members and trained over a larger part of the duplex pulley, a second cable secured to the latter mentioned door, and trained over a guide pulley to provide spaced runs, the free end of the cable being connected to the other door, a tripping rail adapted to be depressed under the weight of the cars, and a connection between the rail and the duplex pulley for separating the latter to open the doors when the rail is depressed, said connection including a cable trained over the smaller part of the duplex pulley and said second mentioned pulley, and means for automatically closing the doors when the tripping rail is released.

4. A mine door, composed of two door members mounted for sliding movement toward and away from each other, means for automatically opening the doors, and including associated large and small pulleys, a cable secured to the large pulley and to one of the door members, a second cable connecting both of the door members, whereby the latter are actuated in unison, a transverse shaft mounted for partial rotation, a tripping rail connected with the shaft and adapted to be depressed by the weight of the cars to rotate the shaft in one direction, a lever carried by one end of the shaft, a cable terminally connected with said lever and trained over the small pulley, a second pulley arranged at a right angle to said small pulley and under which the latter mentioned cable is trained, whereby said cable is actuated to open the doors when the trip rail is

depressed, and means for automatically closing the doors incident to the release of the tripping rail.

5. A mine door, composed of two door members mounted for sliding movement toward and away from each other, car actuated means for automatically opening the doors, means for automatically closing the doors, and each door comprising a plurality

of hingedly connected sections susceptible of being swung in either direction through the door opening, singly or in unison, and resilient means connecting the respective sections of each door for normally holding the latter in door forming positions.

In testimony whereof I affix my signature.

JOHN H. MILLER.
